UNITED STATES PATENT OFFICE.

GEORGE MCADAMS, OF VEVAY, INDIANA.

IMPROVEMENT IN COOKING-STOVES.

Specification forming part of Letters Patent No. 140,210, dated June 24, 1873; application filed March 15, 1873.

To all whom it may concern:

Be it known that I, GEORGE MCADAMS, of Vevay, in the county of Switzerland and State of Indiana, have invented a new and Improved Cooking-Stove, of which the following is a specification:

In the accompanying drawings, Figure 1 represents a front view of my improved cooking-stove. Fig. 2 is a vertical section of the same on the line *c c*, Fig. 3. Fig. 3 is a vertical transverse section on the line *x x*, Fig. 4; and Fig. 4 is a detail section of the wedge-strips used for connecting the cast and sheet iron sides of the stove.

Similar letters of reference indicate corresponding parts.

The object of my invention is to furnish to the public a cheap, simple, and effective cooking-stove, constructed in such a manner that the different parts may be easily packed and shipped, to be mounted by any tinsmith, and the parts exposed to the fire easily replaced. The oven is placed below the fire-box, and supplied with a steady uniform heat around both sides, baking thereby to the satisfaction of those using the stove. My invention consists in the combination of sheet and cast iron parts in such a manner that the front, back, and top plates are of cast-iron, the side and bottom plates of sheet-iron, the interior parts, also, being of sheet and cast iron, and connected by wedge strips of sheet or solid iron. The flues are arranged so that the draft carries the heat from the fire-box around the oven and below the bottom of the same up the chimney.

In the drawing, A represents the front, B the rear, and C the top plate, of cast-iron, which are connected by piece D of sheet-iron, forming the sides and bottom of the stove. The connection of the cast and sheet iron is made by wedge-strips E, of sheet or solid iron, as may be preferred, of square shape, fitting into grooves formed by projecting ribs *a* of the cast-iron plates. Small screw-bolts and nuts *b* rivet strip E through suitable holes to the cast-iron plates, wedging the turned-down rims of the sheet-iron plates firmly between ribs *a*. A substantial connection of the body of the stove is thereby ob-

tained, which may fully sustain the interior parts. Front plate A is cast with suitable apertures for the doors of fire-box, ash-pit, oven, and flue, and also with proper ornamentation, to present a pleasing exterior. Rear plate B has apertures for the damper and insertion of the pipe I, leading to the chimney, and top plate C is open over the fire-box and extended beyond the rear plate B for the purpose of giving support to the pipe I, and available space for the placing of cooking-vessels and other objects. This extension *d* is perforated by symmetrical ornaments to make the top plate lighter. Suitable moldings at top and bottom parts are cast to the front and rear plates A and B. The interior of the stove is also constructed of sheet and cast iron, the parts exposed to the fire being of cast-iron, those not directly in contact with sheet-iron. The fire-box F is arranged immediately under top plate C, and is formed of curved fire-plates *e*, which rest on lugs of plates A and B, and in recesses of the side plates of the ash-pit. They extend side-wise under top plate C, so that no fuel, water, or other impurities may fall into the lower part of the stove. The grate *f* rests also on the recesses of the plates of the ash-pit, and is also made of cast-iron. Side plates *g*, of ash-pit G, are also of cast-iron, reversible, and riveted by their projecting flanges *i* to the top part of the oven H, supporting and bracing the front and rear plates. Oven H is arranged under ash-pit G, extending almost to the whole width of the stove, and constructed of sheet-iron. The top part *m* may be made of one sheet, and riveted to the bottom sheet *n*. Below the bottom *n* of oven H are vertical sheets K leading obliquely from the rear plate toward the front plate, to carry the draft forward and around them back under the bottom to pipe I, enveloping thus the oven completely, and producing uniform baking of the same. The gases of combustion pass over to fire-plates after heating evenly all the vessels of the top plate, then down along the sides around the oven H, and, by means of sheets K, under the bottom of the same to the chimney, as indicated by arrows in Figs. 2 and 3. The damper J, at

rear end of fire-box F, connects, by a corresponding aperture of pipe I, directly with the chimney, and is opened to start the fire, and kept closed when the oven is used; also, to utilize the full amount of heat from the fuel. Damper-rod l, projecting sidewise, opens and closes the damper at will.

The cast-iron plates may be packed in boxes and shipped at less expense to any place, to be put up and mounted by a tinsmith.

Having thus described my invention, I claim

as new and desire to secure by Letters Patent—

1. The arrangement of cast-iron plates A, B, and C, with sheet-metal side and bottom pieces D, substantially as described.

2. The connection of plates A B C having ribs a, by wedge-strips E and bolts b, with sheet-iron sides D, as set forth.

GEORGE MCADAMS.
